(57) **CLAIM**

The ornamental design for a TV tray table, as shown and described.

DESCRIPTION

FIG. 1 is a right rear-side view of the TV tray table showing my new design in the upright position;

FIG. 2 is a right side profile view thereof;

FIG. 3 is a rear profile view thereof of the TV tray table is in its collapsed position showing how the top folds down; FIG. 4 is a rear view thereof showing a partially collapsed position; and,

FIG. 5 is a top view showing a totally collapsed position. The broken lines are for environmental purposes only and form no part of the claimed design.

The front of the TV tray table is flat and unornamented.
